UNITED STATES PATENT OFFICE.

JOHN F. BAKER, OF MANSFIELD, OHIO, ASSIGNOR TO WESTINGHOUSE ELECTRIC & MANUFACTURING COMPANY, A CORPORATION OF PENNSYLVANIA.

FURNACE.

Application filed July 27, 1926. Serial No. 125,141.

My invention relates to furnaces and particularly to rotary furnaces having automatic dumping means.

An object of my invention is to provide 5 an efficient means for automatically effecting the discharge of material from a furnace.

Another object of my invention is to provide, in a rotary furnace, stationary means for periodically causing the discharge of 10 heat-treated material therefrom.

Other objects of my invention will be apparent from the disclosure.

In the present embodiment of my invention, I provide, in a furnace having a conveyor with hearth-trays pivoted thereon, a continuous track having a raised portion opposite the discharge outlet. The free edges of the trays engage the track, and the trays are successively tilted by the raised portion 20 of the track when they arrive opposite to the discharge outlet.

In the drawing, Fig. 1 is a vertical sectional view of a furnace embodying my invention; and

25 Fig. 2 is a section taken on the line II-II of Fig. 1.

Referring to the drawing for a more complete disclosure of the present embodiment of my invention, an annular furnace 10 comprises inner and outer casings 11 and 12 between which are positioned walls 13 of refractory insulating material. The walls 13 enclose a chamber 15 of annular shape. A plurality of heating elements 17 are located 30 in the chamber and secured to the walls thereof and are adapted to be connected to a suitable source of electric energy. A circular run-way or passage-way 20 is formed in the bottom of the furnace, opening at its top 35 into the chamber 15 and adapted to receive an annular conveyor 22.

The annular conveyor 22 comprises a refractory insulating portion 24 that is supported by a bottom member 25. The conveyor 22 is rotatably supported on a circular track 27 by means of wheels 29 that are rotatably mounted on bearing members 30, shown as being integral with the member 25.

A plurality of hearth-tray supporting 50 members 32 are secured to the top of the insulating portion 24 of the conveyor 22. Each support 32 has a hearth tray 33 pivoted to its outer edge by means of the pivot pin 34. The hearth-trays 33 are preferably wider 55 than the support 32 to permit a flange mem-

ber 36 to be secured at the bottom of the tray.

Each flange member has rollers 38 mounted thereon and these rollers engage a stationary circular track 40 that is secured to the bottom of the heating chamber 15 near its inner 60 wall. The track 40 has a raised portion or ramp 41 that is positioned opposite to a discharge outlet 43. The discharge outlet 43 has its outer end extending into oil or other sealing material in the quench tank 45. The 65 edges of the bottom member 25 of the conveyor 22 are provided with concentric annular channel members 47 and 48. The channel members are adapted to contain sand or other sealing material. Co-operating respectively with the channel members 47 and 48 are a pair of concentric circular flange members 49 and 50 secured to the bottom of the furnace and having depending portions immersed in the sand of the channel members 75 to form seals.

Means are provided to drive the conveyor, and, in the present embodiment, such means comprises an annular rack 52 with which the portion 25 of the conveyor is provided, a bevel gear wheel 53 and a shaft 54 therefor that is rotatably mounted in a bearing member 55. The opposite end of the shaft 54 is keyed to a bevel gear wheel 56 that meshes with a bevel gear wheel 57 which is keyed to a vertical shaft 60 having suitable bearings 61 and 62 and being held in position by means of a collar 63.

A bevel gear wheel 65 is keyed to the upper end of the shaft 60 and meshes with a bevel gear wheel 66 that is keyed to the shaft 67 of a worm gear speed-reduction unit 68. In the present embodiment of my invention, the prime mover is an electric motor (not shown) which is operatively connected to shaft 69 95 of the worm gear 68.

From the foregoing description, it will be apparent that, when the shaft 69 is rotated by a motor which receives energy from a suitable source, the shaft 60 will be driven and 100 will, in turn, drive the shaft 54 which, by means of gear wheel 53 and rack 52, will drive the conveyor 22. The conveyor will, therefore, rotate within the passage-way 20. Rotation of the conveyor 22 causes the trays 105 33 to travel through the annular chamber 15. The rollers 38 of the trays 33 will roll along the track 40 and, when a tray 33 arrives opposite to the discharge outlet 43, the rollers 38 will engage the raised portion 41 of the 110

track 40 and thus cause the tray 33 to be tilted about its pivot 34.

In the case of a heat-treating furnace, material that has been placed on the tray to be heat treated will pass through the annular chamber 15. The speed of rotation of the conveyor 22 may be so determined by choice of proper gear wheels as to insure that the material on each tray will be heat-treated for the proper length of time. When a tray arrives opposite the discharge outlet 43 and is tilted in the manner heretofore described, material thereon will be discharged through the outlet 43 into the quench tank 45. As is apparent from the description, the conveyor 22 will be rotated continuously and my automatic dumping means is particularly useful in a rotary furnace of this type.

However, it is, of course, obvious that such dumping means could be used if the conveyor were operated intermittently. It is also obvious that this dumping means could be employed in connection with a conveyor of elongated, or of other shape.

While I have shown and described, for purposes of illustration, a particular form of my invention, it may, of course, be embodied in other forms without departing from the spirit and scope thereof, as set forth in the appended claims.

I claim as my invention:

1. The combination with a heat-treating furnace having an annular heating chamber, of a rotary conveyor having a plurality of tiltable material-receiving trays and adapted to move said trays through said chamber,

means for continuously driving said conveyor, and a ramp for periodically and successively engaging said trays to cause them to tilt and discharge heat-treated material therefrom, said trays being brought into operative engagement with said ramp by the rotation of said conveyor.

2. The combination with a heat-treating furnace having an annular heating chamber, of a rotary conveyor having a plurality of pivotally mounted material-receiving trays thereon, means for continuously driving said conveyor, said conveyor being adapted to move said trays through said chamber, an annular track having a raised portion in said chamber, each of said trays being provided with roller means at its free edge for engaging said track, whereby the rotation of said conveyor will bring the roller means of the trays into engagement with said raised portion to cause the periodic and successive tilting of said trays and the discharge of heat-treated material therefrom.

3. In a furnace, in combination, a conveyor, means for driving the conveyor through the furnace, material-receiving trays pivotally mounted at one side thereof on the conveyor, rollers at the other side of the trays, and a track in the furnace for engaging the rollers to support the other end of the trays, the track having a raised portion to effect a tilting of the trays in succession.

In testimony whereof, I have hereunto subscribed my name this 13 day of July, 1926.

JOHN F. BAKER.
